INVENTOR
JAY A. STOUGH
BY
Arthur C. Morris
ATTORNEY

UNITED STATES PATENT OFFICE

JAY A. STOUGH, OF TULSA, OKLAHOMA, ASSIGNOR, BY MESNE ASSIGNMENTS, TO THE
PHILIP CAREY MANUFACTURING COMPANY, A CORPORATION OF OHIO

TANK

Application filed January 9, 1928. Serial No. 245,602.

My invention relates to oil storage tanks and more particularly to roofs of such tanks, the principal objects of the invention being to protect the contents of the tank from ignition by static electricity or lightning, to seal the tank against leakage of gases emanating from the contained liquid and to provide roof elements having properties resistant to penetration and non-susceptible to disintegration by gaseous or fluid elements whereby the serviceability of the tank cover may be prolonged.

In accomplishing these and other objects of the invention I have provided improved details of structure, the preferred forms of which are illustrated in the accompanying drawings, wherein:

Fig. 1 is a perspective view of an oil storage tank embodying my invention.

Fig. 2 is an enlarged vertical sectional perspective of the upper part of a tank wall and a part of the roof structure.

Fig. 3 is a fragmentary sectional perspective view of the tank roof illustrating the attachment of a metallic binding strip to the roofing overlap.

Fig. 4 is a fragmentary sectional perspective view of the tank roof illustrating the connection of the sections of a metallic binding strip.

Referring in detail to the drawings:

1 designates an oil storage tank of ordinary construction except for the improvements hereinafter described, comprising a cylindrical side wall 2 of sheet metal having a metallic angle ring 3 riveted to its upper edge with the horizontal flange 4 extending outwardly to receive the outer margin of roof covering 5, presently described. Posts 6 attached to the side wall support beams 7; and girders 8 are supported from the beams and from a center pillar 9.

Sheathing 10 is laid on the girders, and the roof covering is built up on the sheathing and flange 4, the roof covering being composed of alternate layers of different types of fiber sheets between which coatings of gas-proof and water-proof materials are interposed for sealing the covering elements together, the

elements comprising the completed covering being applied in the following order:

A layer of fabric roofing material 12, preferably asbestos, is first superimposed on the sheathing and over said angle ring flange, a cement coating 13 impervious to water and gases is spread over the fabric element, and an overlying layer of insulating material 14, of sufficient thickness to provide insulation from sun rays, is applied to the cement and thereby sealed to the fabric. A second cement coating 15 similar to the coat 13 is applied to the top surface of the insulating material, and a layer of roofing material 16, preferably comprising parallel bands or strips of asbestos overlapping as indicated at 17, is laid on the cement and thereby sealed to the insulating material.

A metallic sectional annulus or ring plate 18 overlies the outer portion of the roof covering, the inner portion of the annulus being sealingly connected with the band elements 16 by asbestos fibrated, flexible cement 19. The outer portion of the annulus is secured to the flange of the angle ring and conductively connected therewith by bolts 20; and lag bolts 21 secure the inner portion of the annulus to the sheathing, the bolts 20 and 21 extending through the intervening roof covering elements.

Overlying the overlapping edge of each of the parallel bands 16 is a sectional metallic strip 22; the strips 22, therefore, being parallel; and extending through the strips and the built-up covering into the sheathing are nails 23 which secure the strips and other roof elements in close assembled relation with the sheathing. The strips thus engaged with the sheathing bind together the overlapped edges of the bands 16.

The strips preferably comprise plane portions 24 and boss-like portions 25; and the nails 23 are inserted through the boss-like portions so that expansion and contraction of the strips will be absorbed by the boss-like portions without loosening the nails from the sheathing. The adjacent ends of the sections of which each strip is composed overlap as indicated at 26 in Fig. 4 whereby conduct-

tion of electricity through the entire strip is assured.

The outer ends of the metallic strips overlap the metal annulus and are secured thereto by lag screws or bolts 27 whereby a conductive relation is established between the strips and the side wall through the metal annulus and angle ring for conducting any electrical charge from the strips to the ground.

10 A strip 28 similar to the parallel strips 22 extends diametrically across said strips in conductive relation therewith, the ends of the strip 28 being conductively connected with the metal annulus similarly to the connection 15 of the strips 22 with the annulus.

The insulating elements of the roof covering associated as described, therefore, provide means for retaining gases, fumes and vapors and are respectively adapted for resisting deteriorating influences of sun rays and vapors, and are relatively non-conductive to electricity. The metal strips collect electricity from the atmosphere, and static electricity generated above the roof will be attracted to 25 the strips, which will conduct electricity to the wall for discharge into the ground, thereby avoiding danger to the roof by lightning or from ignition of escaping gases by static sparks.

30 What I claim and desire to secure by Letters Patent is:

1. In a tank having a metallic side wall and a roof including elements non-conductive to electricity, a conducting strip comprising 35 overlapping sections each having a plurality of resilient bosses, the strip extending across the roof and having conductive relation with said side wall, and means bearing on said resilient bosses engaging said elements and 40 attaching the strip to the roof.

2. A tank of the character described including a metallic side wall, a metallic angle ring at the top of said wall, a covering overlying said ring including an element having 45 overlapping edges, and a metallic sectional annular plate overlying the outer edge of the roof covering and bolted to said angle ring, spaced metallic strips binding said overlapping edges of the covering element, the outer 50 ends of the strips bolted to the ring plate, and a transverse metallic strip conductively connected with the spaced metallic strips, the ends of the metallic strip being bolted to the plate.

55 3. In combination with a tank having a metallic side wall, a roof including strips of non-conductive material having overlapping edges, attaching strips of conductive material including base portions overlying thelapping portions of the roof strips and bosses integral with said base portions, and means extending through said bosses for attaching said strips to the tank roof, the ends of said attaching strips being in conductive relation 60 to the metallic wall of the tank.

4. In combination with a tank including a metallic side wall and a top structure including sheathing and strips of non-conductive material above the sheathing having overlapping edges, fastening strips overlying the edges of the cover strips including upstanding bosses and fastening members extending through the bosses and non-conductive strips to said sheathing for attaching the non-conductive and conductive strips to the 75 tank top, the ends of the fastening strips being in conductive relation with the side wall of the tank.

5. In combination with a tank having a metallic side wall and a top including sheathing and parallel, transverse strips of non-conductive roofing material, fastening strips extending across the tank top having base portions covering the adjacent edges of the non-conductive strips and having upstanding expansion bosses, and fastening devices extending through said bosses to the tank top for attaching the fastening strips and cover strips to the roof, the ends of the fastening strips being in conductive relation with the side wall of the tank.

6. In combination with a tank having a metallic side wall and a top including sheathing and parallel transverse strips of non-conductive roofing material, fastening strips extending across the tank top having base portions covering the adjacent edges of the non-conductive strips and having upstanding expansion bosses, fastening devices extending through said bosses to the tank top for attaching the fastening strips and cover strips to the roof, the ends of the fastening strips being in conductive relation with the side wall of the tank, and a conductive strip extending across the tank top in conductive relation with said fastening strips and with the side wall of the tank.

In testimony whereof I affix my signature.
JAY A. STOUGH.
